(57) **CLAIM**

The ornamental design for a rotatable front panel for a modular power storage system as shown and described.

DESCRIPTION

FIG. 1 is a perspective view of a rotatable front panel for a modular power storage system showing our new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The dashed broken lines in FIGS. 1-7 are to illustrate structure that is not part of the claimed design, but shows the environment in which the design is associated, namely a boundary between a planar surface and a curved surface. This includes portion(s) of an article in which the design is embodied, or applied to, that is not considered part of the claimed design.

The dash-and-dot broken lines in FIGS. 1, 4 and 5 are to illustrate structure that is not part of the claimed design, but shows the environment in which the design is associated, namely a cutout on a side surface. This includes portion(s) of an article in which the design is embodied, or applied to, that is not considered part of the claimed design.
